UNITED STATES PATENT OFFICE.

MORRIS U. BERNHEIM, OF CINCINNATI, OHIO, ASSIGNOR TO THE ALVEY-FERGUSON COMPANY, OF OAKLEY, CINCINNATI, OHIO, A CORPORATION OF OHIO.

SPIRAL CONVEYER.

1,250,777.

Specification of Letters Patent. Patented Dec. 18, 1917.

Application filed January 27, 1915. Serial No. 4,592.

To all whom it may concern:

Be it known that I, MORRIS U. BERNHEIM, a citizen of the United States, residing at Cincinnati, in the county of Hamilton and State of Ohio, have invented certain new and useful Improvements in Spiral Conveyers, of which the following is a specification.

This application is filed as a continuation 10 in part of my application Serial No. 696,918, filed May 13, 1912, which resulted in the grant of Letters Patent of the United States No. 1,129,781 the disclosure in the present application differing from the disclosure 15 in said application 696,918 merely in the inclusion of the locking means shown in Figure 5.

The invention primarily consists of a conveyer having an internal longitudinal member 20 which supports a series of ways extending spirally around the same, said ways having adjacent ends or terminals relatively arranged to provide a junction intermediate the length of the conveyer, two of said ways 25 (hereinafter designated "first spiral" and "second spiral" respectively) being disposed at one side of said junction, while another way (hereinafter termed "third spiral") is arranged at the other side of said junction, 30 there being at said junction an opening in the bed or way of the conveyer and a pivotally adjustable member of the bed or way is adapted to bridge said opening and to serve as a means by which the "third spiral" 35 is directly connected with one of the other spirals, the adjustability of said bridging member enabling communication of the "third spiral" with the "first spiral" and and "second spiral," alternately, to be controlled.

The invention also consists in certain peculiarities in the construction and arrangement of parts, and in novel combinations of elements substantially as hereinafter 45 scribed and particularly pointed out in the subjoined claims.

In the accompanying drawings, wherein like characters of reference designate like parts in the several views:

50 Fig. 1 is an elevation of part of a conveyer of the incased type, embodying the present improvements, a part of the casing being broken away.

Fig. 2 is a view on a larger scale of the 55 portion of the conveyer at the junction of

the three ways, showing the third way connected to the other ways, in full and broken lines, respectively: the casing being shown in section.

Fig. 3 is a transverse section on the line 60 3—3 of Fig. 2.

Fig. 4 is a view showing the junction of the three ways, embodying a structure wherein the central supporting member is divided transversely and has its two portions offset from each other, with the adjustable section of the bed modified to adapt it for use with such a member; and

Fig. 5 is a detail view showing a means which may be used to hold the bridging 70 member in its raised position.

In Figs. 1-3, inclusive, of the drawings, A designates the internal supporting member, B designates the "first spiral," C designates the "second spiral" and D designates 75 the "third spiral." Each of these spirals extends around and is suitably connected to said supporting member A. The "first spiral" B and the "second spiral" C are disposed about a portion of the supporting 80 member A which may be considered to be a common portion of the latter, being at one side of what is herein referred to as a junction, while the "third spiral" D is arranged at the other side of said junction, 85 the three spirals having their ends relatively arranged to provide a space which separates the end of the "third spiral" from the ends of the other spirals, and the portion of the bed or way which is arranged at the junction thereof comprises an adjustable section E which is adapted to bridge said space and is such that by its mere adjustment the "third spiral" is thrown into direct communication with either the "first spiral" or 90 the "second spiral," at will. The spiral ways may be of any suitable kind but preferably are of the smooth blade type.

The first and second spirals B and C terminate approximately on the same level, 100 and the bridging member, E, is preferably provided at top and bottom respectively with flanged collars e and e' to or between whose flanges, marked 11, the inner edge 12 of the bridging member is suitably secured, 105 as by rivets 13. The collars are rotatably mounted on the post A, and suitable stops are provided to define the limits of the pivotal movement of the bridging member about said post to those in which its lower 110

edge is alined with the upper edges of the spirals B and C, respectively. This bridging member is preferably supported by a collar 14 fixed to the post and engaging the lower collar, e' , and the means referred to for limiting the movement of the bridging member is preferably composed of projections 15 which are spaced apart on the collar 14 and are arranged in the path of movement of the flange or flanges 11 of the lower collar e' .

The bridging member E is curved and pitched, forming a spiral section of the bed or way, and is such that it may be adjustable to bridge the space between the spiral D and spiral B, as shown in full lines in Figs. 1 and 2, or to bridge the other space between the spiral D and the spiral C, as shown in dotted lines in Fig. 2. It is true that when the bridging member E is moved to bring its lower end into registry with the spiral C, there will be a space between the lower end of the spiral D and the face of the bridging member E but the angle of this bridging member is such that packages falling therefrom will be effectively directed upon the spiral C. No objectionable jar or shock will result because the inclination of the bridging element is in the direction of the line of travel of the packages.

The construction shown in Fig. 4 is particularly devised for use when for any reason it is not practicable to use a continuous post extending through the floor. The post in this event is divided, its two sections being marked A^{20} and A^{21} respectively. The section A^{20} carries the two spirals B^{20} and C^{20} , and the section A^{21} carries the spiral D^{20} , the spiral D^{20} in this particular case being separated from the spirals B^{20} and C^{20} by a space which is bridged by an adjustable member, E^{20} , one of whose edges is hingedly secured at 20 in proximity to the end of the spiral D^{20} , its other end being free to swing from the spiral B^{20} to the spiral C^{20} , as shown by the full and dotted lines respectively in said Fig. 4.

The conveyer preferably includes an outer casing of suitable kind, having feed and discharge openings at the various floors, said casing serving to inclose the spirals and the central supporting member, being spaced from the latter sufficiently to receive the spirals and having its inner wall adjacent to the edges of the spirals. The casing, shown in Figs. 1-3, inclusive, is marked F and its openings, marked F', are provided with suitable doors, as usual. The casing in Fig. 4 is marked F^{20} and has an offset part, as shown, to adapt it to the offset arrangement of the spirals and post shown in said figure.

A conveyer embodying the present improvements will be found to be useful in many cases and may serve any number of

floors. For example, its ways B and C may be employed respectively to carry packages intended to be discharged at different places, or for packages of different characters, receiving said packages from the way D, common to all such packages. To illustrate, let us assume that the conveyer serves thirteen floors through which it extends and that the blades or ways B and C are respectively intended for "charge packages" and "paid packages" and extend from the seventh floor downward, the blade D extending from the seventh floor upward into the thirteenth floor. Attendants place both charge packages and paid packages on the blade D, above the seventh floor, and these packages are thence conducted by said blade to the seventh floor at which the junction of said blade D with the blades B and C is located, and by proper manipulation of the bridging member of the way, at said junction, is delivered to the appropriate blade B or C. It is desirable for such, and for many other uses of the conveyer, to provide means whereby the adjustable bridging member may be adjusted from any of the floors which are served by the blades D. Any suitable adjusting means may be employed. The one illustrated in Figs. 1, 2 and 3 comprises teeth 50 on the collar e , said teeth intermeshing with an appropriate gear 51 carried by a shaft 52 having a sprocket or gear 53 which is engaged by racks 54 and 55 connected with an endless cable whose runs or strands are designated 56 and 57, respectively. This cable extends over a suitable pulley 58 above and under a suitable pulley 59, below. The cable may be operated from any of the floors served by the blade D and its strands 56 and 57, preferably have on each floor buttons marked 60 and 61, respectively, or other suitable means, for convenience in operating them. Obviously, the position of the buttons will indicate the position of the adjustable member of the bed. By pulling upward one of the strands or runs of the cable, the adjustable member of the bed will be moved from the position in which it connects the blade D with one of the blades B or C to the position in which it connects said blades D with the other of said blades B or C, and by pulling the other strand or run of the cable upward the blade D will be restored to its former position, the relative positions of the buttons disclosing which of the blades B or C is in operative relation with the adjustable member of the bed. A suitable means, indicated at 62, for maintaining tension on the cable, or for taking up slack thereof, will preferably be employed in practice, but as such means are commonly used with cables, chains or the like, it is considered to be unnecessary to describe the same in detail herein.

In the form shown in Figs. 4 and 5 the bridging member E^{20} , has a lateral projection which traverses a slot 201 in the casing and is engaged by a suitable raising and lowering means, as the endless cable 202, or the like, shown in said figure, said cable also having buttons 203 on both of its strands. In this form of the invention the third spiral D^{20} is connected alternately with the 5 first spiral B^{20} and second spiral C^{20} by raising and lowering the bridging member E^{20} , the latter swinging from its pivoted end 20. This raising and lowering of the bridging member is accomplished by proper 10 manipulation of the endless cable. In practice suitable means are provided whereby the bridging member is held in its proper correlation with the first spiral B^{20} while a package is passing thereover to said spiral, 15 the means referred to being of a nature such as to release the bridging member when it is desired to lower the latter. Fig. 5 shows a desirable means of the kind referred to. This comprises a spring pressed bolt 204 20 carried by the bridging member, a bolt actuator 205 movable with the cable and a latch 206 pivoted to the casing. This particular embodiment of the invention is embraced in an application for Letters Patent 25 of the United States executed of even date herewith and need not be herein more particularly set forth.

It will be understood that the spirals B^{20} and C^{20} may be employed for "charge packages" and "paid packages" or for packages intended to be discharged at different places, or for packages of different characters and that these spirals, as well as the spiral D^{20} , may extend through any number of floors 30 in a building.

It also will be noted that the correlation of the spirals and adjustable bridging means in each of the particular embodiments of the invention herein described is such that packages are delivered from the third spiral to the first spiral or second spiral, at will, by the mere adjustment of the bridging means and it will be noted further that the correlation of the parts is such that the delivery of the packages between the third spiral and the other spirals is a direct one, the adjustable switching member in none of the herein exemplified forms of the invention serving to carry the packages to discharge 45 openings in the casing or away from the conveyer, or to other conveying mechanisms.

Again, it will be noted that while the conveyer has been described with reference to the use of the third spiral as a means for 50 feeding packages to the first and second spirals, it will not be a departure from the spirit of the invention to reverse this relative arrangement of the spirals, that is to say, to correlate the parts in either of the 55 embodiments herein exemplified so that

packages will be fed by the first and second spirals to the third spiral. It will further be noted that, while the conveyer has been exemplified as extending through the floors of a building, it may be arranged outside 70 of the building. These and other changes in the exemplified construction and arrangement of parts are contemplated to be within the spirit of the invention and the scope of the subjoined claims. 75

Having now described the invention what I believe to be new and desire to secure by Letters Patent, is:—

1. A conveyer comprising a plurality of ways spirally disposed and with helices of 80 one arranged between helices of the other, a member having an end for operative connection with either of said ways, said member being adjustable to shift its said end from either way to the other, and another 85 spirally disposed way operatively related to the other end of the adjustable member in the different positions of the latter.

2. A conveyer comprising a plurality of spiral ways having a common longitudinal 90 axis and with helices of one arranged between helices of the other, a bridging member having an end for operative connection with either of said ways, said member being adjustable to shift its said end from either 95 way to the other, and a third spiral way whose axis is substantially alined with the axis of the other ways and whose end is spaced from the ends of the latter ways, 100 said bridging member being mounted in the space between the third way and the first mentioned ways and having its end opposite the latter in operative relation with the third way in its different positions of adjustment. 105

3. A conveyer, comprising an internal supporting means, a first spiral and a second spiral extending around one part of said means, a third spiral extending around another part of said means and having its 110 terminals spaced from the terminals of the first and second spirals, and a pivotally adjustable member for bridging the space between the third spiral and either of the other spirals, at will. 115

4. A conveyer comprising an internal supporting means, two ways extending spirally about a common part of the internal supporting means, a third way extending spirally about a different portion of the internal supporting means, said ways having their ends correlated to provide a space between the third way and the first two, and a member mounted in said space and constituting a section of a spiral; for transferring packages between the third way and either of the others, said member being adjustable to shift one of its ends from operative relation with either of the first mentioned ways 120 into operative relation with the other and 130

being operatively related to the third way in either of its positions.

5. A conveyer comprising an internal supporting means, a plurality of ways coiled spirally about a common part of the internal supporting means, a separate way coiled spirally about a different part of the internal supporting means and having its end spaced from the ends of the first mentioned ways, a casing inclosing the ways, and a member in said casing for transferring packages between said separate way and either of the other ways, said member being mounted in the space between the ways and adjustable to shift one of the ends from operative relation with either of the first-mentioned ways into operative relation with the other of the same, its other end being operatively related to said separate way in either position of the member.

6. A conveyer comprising a plurality of spiral ways disposed in a common portion of the conveyer, a member having an end for operative connection with either of said ways, said member being adjustable to shift its said end from either way to the other, means for adjusting said member from different places, and another spiral way operatively related to the other end of the adjustable member in the different positions of the latter.

7. A conveyer comprising an internal supporting means, a plurality of ways extending spirally about a common portion thereof, a third way extending spirally about a different portion of the internal supporting means, and having its end spaced from the ends of the first mentioned ways, an adjustable member for bridging the space between the separate spiral way and either of the other spiral ways at will, said member being adjustable and so correlated with the ways that one of its ends will be movable from one to the other of the first mentioned spiral ways and its other end will be in operative relation with the separate spiral way in the different positions of the member, and an outer casing encircling said ways.

8. A conveyer comprising an internal supporting means, a plurality of ways extending spirally about a common portion thereof, a third way extending spirally about a different portion of the internal supporting means, and having its end spaced from the ends of the first mentioned ways, an adjustable member for bridging the space between the separate spiral way and either of the other spiral ways at will, said member being adjustable and so correlated with the ways that one of its ends will be movable from one to the other of the first mentioned spiral ways and its other end will be in operative relation with the separate spiral way in the different positions of the member, an outer casing encircling said ways

and means comprising an endless element arranged outside the casing and extending lengthwise thereof and having connection with the bridging member for adjusting the latter from various places in the length of the conveyer.

9. A conveyer comprising a plurality of spiral ways disposed in a common portion of the conveyer, a member having an end for operative connection with either of said ways, said member being adjustable to shift its said end from either way to the other, an endless element having connection with the adjustable member and extending lengthwise of the conveyer for adjusting said member from different places in the length of the conveyer, and another spiral way operatively related to the other end of the adjustable member in the different positions of the latter.

10. A conveyer comprising a plurality of spiral ways disposed in a common portion of the conveyer, a member having an end for operative connection with either of said ways, said member being adjustable to shift its said end from either way to the other, a separate spiral way operatively related to the other end of the adjustable member in the different positions of the latter, and means for adjusting the adjustable member from different places in the length of the conveyer, said means comprising an endless element having connection with the adjustable member, rollers above and below the adjustable member and engaged by the endless element, and buttons on both runs of the endless element.

11. A conveyer comprising a plurality of spiral ways having corresponding ends disposed in substantially the same horizontal plane, a separate spiral way having an end spaced from said end of the first mentioned ways, and a pivotally mounted section arranged in said space with one of its ends in operative relation with the end of said separate spiral way and its other end shiftable into operative relation from either of the first mentioned spiral ways to the other of the same.

12. A conveyer comprising a plurality of spiral ways disposed with helices of one between helices of the other, said ways having corresponding ends arranged in substantially the same horizontal plane, a separate spiral way having an end spaced from said ends of the first mentioned ways, and a pivotally mounted section arranged in said space with one of its ends in operative relation with the end of said separate spiral way and its other end shiftable into operative relation from either of the first mentioned spiral ways to the other of the same.

13. A conveyer comprising a plurality of spiral ways having a common longitudinal axis, a separate spiral way spaced from the

first mentioned ways and whose axis is substantially in line with the axis of the latter and a pivotally bridging section constituting a section of a spiral and disposed in the 5 space between the first mentioned spirals and said separate spiral with its axis substantially alined with the axes of said spirals.

14. A conveyer comprising an internal 10 supporting means, a plurality of spiral ways extending about a common part of the internal supporting means, a separate spiral way extending about a different part of the internal supporting means and having its 15 ends spaced from the ends of the latter, and a member pivotally adjustable about the internal supporting means and arranged in said space, said member constituting a section of a spiral and having one of its ends 20 movable from operative relation with either of the first mentioned spirals into operative relation with the other of the same and its other end in operative relation with said separate spiral in the different positions of 25 the member.

15. A conveyer comprising an internal supporting means, a plurality of spiral ways extending about a common part of the internal supporting means and having corresponding ends approximately at the same 30 level, a separate spiral way extending about a different part of the internal supporting means and having its ends spaced from the ends of the latter, and a helical member 35 pivotally adjustable about the internal supporting means and arranged in said space with one of its ends in operative relation with the separate spiral way in its different positions and its other end movable from 40 operative relation with either of the other spiral ways into operative relation with the other of the same.

16. A conveyer comprising an internal supporting means, a plurality of ways extending 45 spirally about a common portion thereof, a separate way extending spirally about a different portion of the internal supporting means with its end spaced from the ends of the first mentioned ways, a helical member 50 mounted in the space between the separate way and the first mentioned ways and provided with collars pivotally mounted on the internal supporting means,

said member being adjustable to connect the separate way with either of the first mentioned ways, and means for defining the limits of its adjustment to those in which it is properly correlated with said ways. 55

17. A conveyer comprising an internal supporting means, a plurality of ways extending spirally about a common portion thereof, a separate way extending spirally about a different portion of the internal supporting means with its end spaced from the ends of the first mentioned ways, a helical member 60 mounted in the space between the separate way and the first mentioned ways and provided with collars pivotally mounted on the internal supporting means, 65 one of said collars having teeth, a rod having a gear to engage said teeth, means for actuating said rod to adjust said member, and means for defining the limits of the adjustment to those in which the helical member connects the separate way with the 70 other ways respectively. 75

18. A conveyer comprising an internal supporting means and an outer casing, a plurality of spiral ways extending about a common part of the internal supporting 80 means and arranged in the casing, a separate spiral way extending around a different part of the internal supporting means and arranged in the casing and having an end spaced from the ends of the first mentioned 85 ways, a helical member mounted in said space and having collars mounted on the internal supporting means, one of said collars having teeth, a rod extending to the outside of the casing and having a gear 90 engaging said teeth, an endless element having connection with the rod and extending longitudinally of the casing and actuating said rod to adjust said member from different points in the length of the casing, 95 and means for defining the limits of the adjustment of the helical member to those in which it connects the separate way with the other ways respectively.

In testimony whereof I affix my signature 100 in presence of two witnesses.
